UNITED STATES PATENT OFFICE.

JOSHUA WHITTEMORE, OF WAKEFIELD, MASSACHUSETTS.

CELLULOID CRUTCH-TOP.

SPECIFICATION forming part of Letters Patent No. 233,824, dated October 26, 1880.

Application filed September 27, 1880. (No model.)

To all whom it may concern:

Be it known that I, JOSHUA WHITTEMORE, of Wakefield, in the county of Middlesex and State of Massachusetts, have invented a new and useful Celluloid Crutch-Top, of which the following is a specification.

My invention relates to the method of rendering light and strong material like wood, papier-maché, and other like compounds suitable for crutch-tops; and it consists in forming the light material into the proper shape and size, and then compressing upon it a coating of some plastic water-proof material—for instance, celluloid, lac compounds, &c.

In the drawings, Figure 1 is an elevation of my crutch-top. Fig. 2 is a vertical section of the same. Fig. 3 is a plan view of the under side.

I carve or mold the body A of the crutch in the proper form. This may be made of any suitable wood thoroughly seasoned, or it may

be made of papier-maché, lac compounds, &c. When properly formed, compressed, dried, and polished, I press upon it a coating, B, of celluloid or some similar compound that has the requisite strength and other needed characteristics. The crutch-top thus made has the advantage of being cheap, light, cool, and water-proof.

C C represent holes for the reception of the ends of the staff.

The molds or dies for making this article should be very smooth and solid.

Having thus described my invention, what I desire to secure by Letters Patent is—

In a crutch-top, the combination of the body A with the compound coating B, substantially as described, and for the purpose set forth.

JOSHUA WHITTEMORE.
